UNITED STATES PATENT OFFICE.

LUKE VINCENT SONNER, OF BUHL, IDAHO.

SICKLE-GRINDER.

1,369,569.

Specification of Letters Patent. Patented Feb. 22, 1921.

Application filed April 3, 1920. Serial No. 370,939.

To all whom it may concern:

Be it known that I, LUKE VINCENT SONNER, a citizen of the United States, and a resident of Buhl, in the county of Twin Falls 5 and State of Idaho, have invented certain new and useful Improvements in Sickle-Grinders, of which the following is a specification.

My invention relates to grinders more 10 particularly adapted for the grinding of the teeth of a sickle, the purpose of my invention being the provision of a grinder having simple and efficient means for rigidly supporting the sickle blade in convenient position for grinding, and driving means for a 15 grinding element which permits of the universal movement of the grinding element so that it can be moved to any desired position with respect to the sickle blade for effecting 20 the desired grinding of the teeth of the blade.

I will describe one form of grinder embodying my invention and will then point out the novel features thereof in claims.

In the accompanying drawings—

25 Figure 1 is a view showing in top plan one form of grinder embodying my invention.

Fig. 2 is a view showing in front elevation the grinder shown in Fig. 1.

Fig. 3 is a view showing the grinder in side 30 elevation.

Fig. 4 is a fragmentary sectional view showing the driving connection between adjacent sections of the driving shaft.

Fig. 5 is a detail perspective view of one 35 section of the bed plate of the machine.

Similar reference characters refer to similar parts in each of the several views.

Referring specifically to the drawings, F 40 designates generally a frame upon which the entire mechanism of the grinder is supported, such frame being formed of flat metallic bars arranged to provide a front rectangular portion 15 and a rear L-shaped portion 16 which is connected to the upper end of the 45 portion 15 and held in proper spaced relation to the lower end of the portion 15 by brace rods 17. Rotatably mounted upon the front portion 15 at a point adjacent its lower end is an operating crank K which is journaled in bearings 18 secured to the vertical bars of the portion 15, as clearly shown in 50 Figs. 2 and 3. The crank K comprises reversely disposed crank portions 19 and 19^a which function as pedals for the feet of an 55 operator in effecting a rotation of the crank. One end of the crank K extends laterally

from the front portion 15 and into a gear casing G in which is adapted to be housed a train of gearing (not shown) of conventional form for appreciably increasing the 60 speed of rotation of the section 20 of a driving shaft S. The driving shaft S is comprised of sections 20, 21, 22 and 23, any two adjacent sections being operatively connected at their confronting ends by a gear 24, 65 as clearly shown in Fig. 4. A portion of the shaft sections of the shaft S are journaled in sleeves 25, such sleeves being preferably connected to each other as at 26 in Fig. 2. As shown in Figs. 1, 2, and 3, the 70 shaft section 23 is relatively short and is adapted to support thereon a grinding element E, such element in the present instance being an emery wheel which has a larger central diameter than either end diameter. The emery wheel E is fixed to the shaft section 23 for rotation therewith and is locked against displacement therefrom by a bearing sleeve 27 formed on one end with a handle 28. The bearing sleeve 27 in turn 75 is locked against displacement in the shaft section 23 by a cotter pin 29.

As shown in Figs. 2 and 3, the frame F is provided with a bed plate B upon which the work to be ground is adapted to be supported. This bed plate B is formed of two L-bars 30 and 31 which are bolted or otherwise secured to the connected ends of the portions 15 and 16 in such manner that they are reversely disposed as is clearly shown 80 in Fig. 3. The front bar 31 has its forward edge formed with teeth 31^a which are designed to conform to the contour of the teeth of a single blade C. The rear bar 30 is provided with upstanding staples 31^b 85 through which extends the divergent portions of a wire shaped yoke Y. The rear end of the main portion of the yoke Y is formed with an eye through which extends a rod 32 that is slidably fitted in a bar 33 90 secured to the portion 16 of the frame F. Surrounding the rod 32 and interposed between the bar 33 and the yoke Y is a coiled 95 expandible spring 34 which serves to bias the rear end of the yoke upwardly and to 100 thereby force the divergent portion of the yoke downwardly toward the bed plate B. As a result of this arrangement it will be seen that the staples 31^b act as fulcrum 105 points for the yoke Y, and as the divergent 110 portions of the yoke project partially across the bed plate B, it will be seen that they

serve to securely clamp a piece of work to the bed plate.

The operation of the grinder is as follows:

- 5 The operator reposes upon a seat T supported upon the portion 16 of the frame F, and with his feet resting upon the cranks 19 and 19^a, rotation of the crank K can be readily effected to drive the shaft S which 10 in turn causes a rotation of the emery wheel E. The sickle blade C is clamped upon the bed plate B by first pressing the rear end of the yoke Y against the tension of the spring 34 thereby lifting the forward ends 15 of the yoke so as to permit the insertion of the blade between the yoke and the bed plate. When applying the sickle blade to the bed plate, it should be seen that the teeth of the blade register with the teeth 20 31^a of the bar 31 whereby, a rigid support is effected for the several teeth at the same time permitting the proper positioning of the emery wheel in grinding the teeth in the desired manner. The sickle blade having 25 been positioned in this manner, the rear end of the yoke Y is released, thereby allowing the spring 34 to force the forward ends of the yoke into engagement with the blade and thus securely holding the same upon the 30 bed plate.

In manipulating the emery wheel, the operator grasps the handle 28 with one hand and the sleeve 25 of the shaft section 22, with the other hand. In this manner the 35 emery wheel can be moved to any desired position with respect to the blade C without in any way impeding the rotation of the wheel. As the shaft S is comprised of universally connected sections, it will be manifest that a wide range of movement is per- 40

mitted of the emery wheel so that it can be moved up or down, or to either side, or at any angle to conform to the bevel of the particular tooth to be ground. It will be further manifest that such range of movement permits nicks in the teeth to be ground or hollowed out to a new edge and without in any way altering the adjustment 45 of the emery wheel or driving shaft.

Although I have herein shown and described only one form of grinder embodying my invention, it is to be understood that various changes and modifications may be made herein without departing from the spirit of the invention and the spirit and 50 scope of the appended claims.

What I claim is:

1. A sickle grinder comprising, a bed plate on the frame, a wire shaped yoke fulcrumed on the bed plate, a rod slidably supported upon the frame and connected to said yoke, a spring on the rod and arranged to bias the yoke toward said frame, a flexible shaft, a grinding element operable by said shaft, and means on the frame 60 for driving said shaft.

2. A sickle grinder comprising, a frame, a bed plate supported on the frame and formed with teeth, a wire shaped yoke fulcrumed on the bed plate, a rod slidably supported on the frame and connected to said yoke, a spring surrounding said rod and arranged to bias the yoke toward said bed plate, a crank shaft journaled on the frame, a flexible shaft comprised of sections universally connected to each other and to said crank shaft, and a grinding element fixed to one of said sections. 70 75

LUKE VINCENT SONNER.
